By his Atty. J. Dennis Jr.

United States Patent Office.

REMUS D. BURR, OF KINGSBOROUGH, NEW YORK.

Letters Patent No. 80,707, dated August 4, 1868.

IMPROVEMENT IN GLOVES.

The Schedule referred to in these Letters Patent and making part of the same.

TO ALL WHOM IT MAY CONCERN:

Be it known that I, REMUS D. BURR, of Kingsborough, Fulton county, State of New York, have invented certain new and useful Improvements in Gloves and Fingered Mittens; and I do hereby declare the following description and accompanying drawings are sufficient to enable any person skilled in the art or science to which it most nearly appertains to make and use my said invention or improvements without further invention or experiment.

The nature of my invention and improvements consists in cutting the front of the hand and thumb and all the fingers of a glove or mit, joined in one piece of leather or other material; also, in cutting the whole or three sides of the fore-finger joined to or in the same piece with the above-mentioned parts; and in cutting the back of the hand and thumb, and the back and sides of the middle and little fingers, all joined in one and the same piece, or cutting the back of the hand and the backs and sides of the middle and little fingers all in one piece; also, in cutting the back and sides of the ring or third finger in one piece, and sewing it to the back of the hand, and in cutting the back of the thumb separate from the back of the hand, and sewing it thereto, and in cutting the front of the thumb separate from the front of the hand, and sewing it thereto; also, in producing a new article of manufacture, by applying my improvements, or some of them, in the manufacture of gloves or mittens.

In the following description of my improved method of cutting and connecting the parts of a glove or mitten, I refer to the accompanying drawings, forming part of this specification.

Figure 1 shows a single piece of leather, or other material, cut to form the front or inside of a glove.

The part A is to be turned over upon the part B, to form the fore-finger complete, the edges *a a* being joined to form a seam, while the part C forms the front and sides of the thumb.

Figure 2 represents, in one piece of stuff, the back of the hand, and the backs and sides of the middle and little fingers of the same glove.

The edges, having the same letters, as *b b*, *c c*, &c., are to be joined to form a seam.

Figure 3 shows the back and sides of the third or ring-finger, and

Figure 4 the back of the thumb.

The edges indicated by the same letter, to be joined to form the several seams and complete the glove.

If preferred, the inside of the fore-finger may be cut separate, and sewed on, forming a seam at the dotted line D E, on fig. 1, and the front or wearing-side of the thumb may, in like manner, be cut separate, and attached to the other part by a seam at the dotted line F G, on the same figure.

Figure 5 represents the front of a one-fingered mitten; the part H to be turned over upon the part I, to form the finger complete, or the inside of the finger may be cut separate and joined by a seam at the dotted line J K, the part L forming the front and sides of the thumb, as in the glove; and

Figure 6 shows the back of the mitten, adapted to cover the back of the hand and three fingers, the back of the thumb being the same as in the glove shown in fig. 4.

If thought desirable, the back of the thumb, for either the glove or the mitten, or for both, may be cut joined to or in one piece with the back of the hand, and the seam or seams formed by the edges *i i* be thus avoided.

What I claim as my invention and improvements in gloves and fingered mittens, is—

1. Cutting the front of the hand, thumb, and all the fingers, joined in one and the same piece of material, substantially as shown and described.

2. In combination with the front, cut in one piece, as above claimed, I claim cutting the whole or three sides of the fore-finger, also joined in said piece, substantially as described.

3. I also claim cutting the back of the hand and thumb, and the back and sides of the middle and little fingers, all joined in one and the same piece of stuff, substantially as described.

4. I claim cutting the back of the hand with the back and sides of the middle and little fingers, all in one piece, as shown and described.

5. In combination with the back of the hand and the middle and little fingers, cut as above claimed, I claim the back and sides of the ring-finger, cut in one piece and sewed to the back, substantially as described.

6. In combination with the elements of the first claim, I claim cutting the back of the thumb separate from the back of the hand, and joining it thereto by a seam.

7. In combination with the elements of the third and fourth claims, I claim cutting the front of the thumb separate from the front of the hand, and joining it thereto by a seam.

8. In combination with the front of a mitten, cut as claimed in the first claim, I claim cutting the back of a mitten with the back of the thumb in one piece, substantially as described.

REMUS D. BURR.
